(57) CLAIM

The ornamental design for a tanning bottle with timer, as shown and described.

DESCRIPTION

FIG. 1 is front elevational view of a tanning bottle with timer showing my new design;

FIG. 2 is a rear elevational view thereof;

FIG. 3 is a side elevational view thereof;

FIG. 4 is a top plan view thereof; and,

FIG. 5 is a bottom plan view thereof.

The broken lines shown in the drawing disclosure are for illustrative purposes only and form no part of the claimed design.
